UNITED STATES PATENT OFFICE.

DANIEL KOPS, OF NEW YORK, N. Y.

APPAREL-CORSET.

No. 813,805.

Specification of Letters Patent.

Patented Feb. 27, 1906.

Application filed October 30, 1905. Serial No. 285,212.

To all whom it may concern:

Be it known that I, DANIEL KOPS, a citizen of the United States, residing in the borough of Manhattan, city, county, and State of New York, have invented a new and useful Improvement in Apparel-Corsets, of which the following is a specification.

In the art of apparel-corsets it has heretofore been usual to provide breast covers or pads or supporters, both for the purpose of creating a form and of sustaining a natural form; and the object of my invention is to provide an apparel-corset with a light-weight flexible shaping-support secured by sewing to the upper edge of the corset and which is adapted to extend across the bust and to have its free ends connected together for tension and support.

In the device of my invention the light-weight flexible shaping-support employed by me is composed in each part of several pieces of fabric at one end secured to the upper edge of a corset, beginning a short distance from the front and extending around toward the sides, the free ends of which pieces converge and are connected.

In use the respective ends of the parts attached to the halves of the corset are arranged to be manually connected in any desired and adjustable relation. The several pieces of each part may be separate or of shaped parts sewed together, and which flexible fabric-support is of such form that when not desired for use it may be turned downward against the outer surface of the corset out of the way.

In the drawings, Figure 1 is a front elevation of the upper portion of a corset of ordinary construction, illustrating the parts constituting my invention as connected in position for use. Fig. 2 is a side elevation of the structure shown in Fig. 1. Fig. 3 is a front elevation of the upper portion of a corset with the devices of my invention turned down out of the way when not in use. Fig. 4 is a side elevation showing the shaping-support of my invention formed of several pieces sewed together and at the broad end sewed to the upper end of a corset, the free end of said parts converging. Fig. 5 is an elevation of the parts of my improved shaping-support, showing a modified form of connecting together the free ends; and Fig. 6 shows a detail.

a and *b* represent the upper portions of halves of a corset of ordinary construction, and *c* the fastening device of the steels at the front for connecting said parts together.

The light-weight flexible shaping-support which forms an essential feature of my invention is shown in Figs. 1 and 2 as formed of a number of pieces of tape 2, 3, 4, 5, 6, and 7, 60 and as each number is alike the description of one will suffice.

The separate pieces 2 to 7, inclusive, are secured to the upper edge of the corset by sewing shown by dotted lines, the piece 2 65 being located a short distance from the front steel and the respective parts being slightly overlapped and extending around toward the sides and toward the under-arm portion of the corset and the free ends of these pieces 2 70 to 7, inclusive, converge and increase in their overlapping as they converge and they are connected together at their free ends by an overlying strap *d*, sewed to all of the free ends, and from which strap *d* extends a tape *e*. 75

The respective pieces 2 to 7, inclusive, are positioned over a form so that in use they will conform to the natural form of the wearer in the supporting function for which they are made. This will be more or less apparent by a view of Figs. 1 and 2, respectively, front and side elevations, and in which the dotted lines indicate the bust outline, the object of said flexible support being of confining the natural figure of the wearer 85 within the boundary limits of the corset, and thus assist in the fitting of a waist and in the general appearance of the figure.

Fig. 1 shows the tapes *e* of the two parts of the shaping-support tied together, so as to 90 draw the shaping-support and apply the desired tension over the figure.

I do not limit myself to tying-tapes or even to the snap-fasteners shown in Fig. 5 for the same purpose, as any desired or convenient 95 device or means may be employed for holding together or connecting the free ends of the shaping-support.

In Fig. 4 I have shown the shaping-support as made of three pieces of fabric *f f' f''*, 100 cut to the desired form and sewed together, and also as with the pieces 2 to 7, inclusive, sewed to the upper edge of the corset.

With the pieces shown in Fig. 4 it is preferable to so shape them as to impart to the 105 flexible shaping-support formed thereby a concave or hollow configuration, so as more nearly to conform to the figure of the wearer.

It is a fact and from the drawings it will be apparent that the shaping-support of my 110 invention is not only to be sewed to the upper edge of a corset of ordinary construction,

but is preferably sewed to the upper edge after the usual binding has been applied to the corset. Therefore should the purchaser of a corset of this form desire for any reason 5 whatsoever to remove the shaping-support it can be done by cutting the sewing and removing the threads without injuring the corset proper in its continuity.

At the left side of Fig. 1 I have shown the 10 multiplicity of pieces 2 to 7, inclusive, as disconnected between their connected converging ends and places of attachment to the upper edge of the corset, while at the right-hand side of Fig. 1 I have shown an overlying tape 15 8, occupying an intermediate position between the place of attachment to the corset and the connected converging ends and which tape is sewed down to place, so as to intermediately connect all the separate pieces 20 2 to 7 together; but I do not limit myself to the employment of such pieces, as it is only a form of the invention.

In Fig. 6, illustrating a detail, I have shown a binding-strip 9 for joining together by sewing 25 the adjacent ends of the parts forming my improved shaping-support, so that each shaping-support is made complete and is adapted to be connected by a line of sewing at its bound edge to the binding at the upper 30 edge of the corset, this construction being fully shown in Fig. 6, which is a cross-section and partial perspective.

I claim as my invention—

1. The combination with the halves of an 35 apparel-corset of ordinary construction, of shaping-supports of flexible material, each formed of a multiplicity of pieces, at one end connected by sewing to the upper edge of the corset from a short distance from the front 40 steels, and extending around toward the under-arm sides and with their free ends overlapped and converging, and connected together, and means for connecting their free ends in an adjustable relation.

45 2. The combination with the halves of an

apparel-corset of ordinary construction, of shaping-supports of flexible material, each formed of a multiplicity of pieces, at one end connected by sewing to the upper edge of the corset from a short distance from the front 50 steels, and extending around toward the under-arm sides and with their free ends overlapped and converging, and connected together, and tying-tapes formed as prolongations of the free converging ends of the shaping-supports, and by which the shaping-supports are tied together for use in an adjustable relation.

3. The combination with the halves of an 60 apparel-corset of ordinary construction, of shaping-supports of flexible material, each formed of a multiplicity of pieces, at one end connected by sewing to the upper edge of the corset from a short distance from the front 65 steels, and extending around toward the under-arm sides and with their free ends converging, and connected together, and means for connecting their free ends in an adjustable relation.

4. The combination with the halves of an 70 apparel-corset of ordinary construction, having a binding along its upper edge of shaping-supports of flexible material, each formed of a multiplicity of pieces, at one end connected together by a binding and sewed thereto, and 75 connected by sewing to the bound upper edge of the corset from a short distance from the front steels, and extending around toward the under-arm sides, and with their free ends converging and connected together, 80 and means for connecting together the free ends of said shaping-supports as extending toward one another over the bust and in an adjustable relation.

Signed by me this 27th day of October, 85
1905.

DANIEL KOPS.
